COMBINATION MAILING CASE AND MYCOLOGY KIT

Raymond S. Michel, Portland, Oreg., assignor to United
Medical Laboratories, Inc., Portland, Oreg., a corpora-
tion of Oregon

Filed June 12, 1967, Ser. No. 7,465

Term of patent 14 years

(Cl. D83—1)

FIG. 1 is a side elevation of a combination mailing case and mycology kit;

FIG. 2 is a bottom interior plan view thereof, with the kit contents removed;

FIG. 3 is a top interior plan view thereof;

FIG. 4 is a reduced bottom interior plan view, with the kit contents in place;

FIG. 5 is a reduced top interior plan view thereof;

FIGS. 6 and 7 are exterior views on a reduced scale of the two identical bottom and top pieces shown respectively in FIGS. 2 and 3 when combined as a mailing case as shown in FIG. 1.

The undisclosed top and bottom exterior portions are plain and unornamented.

I claim:

The ornamental design for a combination mailing case and mycology kit, as shown and described.
